UNITED STATES PATENT OFFICE.

JOHN F. O'CONNOR, OF CHICAGO, ILLINOIS, ASSIGNOR TO WILLIAM H. MINER, OF CHAZY,
NEW YORK.

DRAFT-RIGGING.

1,307,307.

Specification of Letters Patent. Patented June 17, 1919.

Application filed September 20, 1916. Serial No. 121,131.

To all whom it may concern:

Be it known that I, JOHN F. O'CONNOR, a citizen of the United States, residing at Chicago, in the county of Cook and State 5 of Illinois, have invented a certain new and useful Improvement in Draft-Rigging, of which the following is a full, clear, concise, and exact description, reference being had to the accompanying drawings, forming a 10 part of this specification.

This invention relates to improvements in draft riggings.

One object of the invention is to provide a draft rigging wherein are employed movable castings or plates having stop shoulders thereon.

Another object of the invention is to provide a draft rigging wherein castings or plates having the usual stop shoulders thereon are secured to and move in unison with the draw bar.

Another object of the invention is to provide a draft rigging wherein the movable means associated with the draw bar for transmitting the pulling and buffing shocks to the followers are provided with limiting stops.

The invention furthermore consists in the improvements in the parts and devices and in the novel combinations of the parts and devices herein shown, described and claimed.

In the drawing forming a part of this specification, Figure 1 is a vertical, longitudinal section of a portion of a car showing my improvements in connection therewith. Fig. 2 is a horizontal, longitudinal section of the structure illustrated in Fig. 1 and taken on the line 2-2 thereof. And Figs. 3. and 4 are vertical, transverse sectional views taken on the lines 3-3 and 4-4, respectively, of Fig. 1.

Referring to said drawing, 10-10 denote channel-center sills of a car, the same being slotted as indicated at 11, to accommodate the back and forth movements of a coupler key 12. Upper and lower plates 13 and 14 are secured to the tops and bottoms of said sills, as indicated in Figs. 1, 2 and 4, said plates preferably forming a part of the bol-

ster of the car. Secured to said plates 13 and 14 are forwardly extended upper and lower castings 15 and 16, the latter at their forward ends being rigidly secured to the centers of upper and lower cross plates 17 and 18 secured to the top and bottom flanges, 55 respectively of the sills. The castings or bars 15 and 16 are provided with vertically alined, substantially rectangular openings 19 and 20, the perforations 19 being adapted to receive a square bar 21 and the perforations 20, a similar bar 22, said bars 21 and 22 being supported by any suitable means such as the cotters 23 that pass through bosses or enlargements 24 on the lower casting 16. The bars 21 and 22 have mounted 60 thereon, between the castings 15 and 16, blocks 25 and 26, the block 25 being preferably rounded, as indicated at 27, on its front and rear faces and against which bear the intermediate followers 28 and 29 of a 65 tandem spring gear. The front main follower 30 of the tandem gear bears against the rear or inner face of the block 26. The rear main follower 31 of the tandem gear normally bears against the front edges of 70 vertically extending webs 32-32 that preferably are formed integral with the bars 15 and 16 (see Fig. 4). Suitable springs 75 33-33 are interposed between the sets of followers 30 and 28, and 29 and 31.

Connected to the draw bar 34 by means of the coupler key 12, are castings or plates 35-35. Each of the castings or plates 35 is in the form of the usual rigid tandem stop castings, that is to say, it is provided 80 with main front and rear stops 36 and 37; intermediate main stops 38 and 39; and limiting stops 40, 41, 42 and 43 opposite the main stops 36, 38, 39 and 37, respectively. As apparent from an inspection of Fig. 2, 85 the followers 30, 28, 29 and 31 normally engage the main stops 36, 38, 39 and 37, respectively. The castings 35-35 engage the inner faces of the sills 10 and slide with respect thereto. The forward ends of said 90 castings are supported by the coupler key 12 and the rear ends of said castings are supported by the cross plate 14.

In operation, upon forward or draft movement of the draw bar, it is apparent that the followers 30 and 29 will be held stationary by the fixed blocks 26 and 25. The 5 remaining followers 28 and 31 will be pulled forwardly through the instrumentality of the castings 35 and such forward movement will continue until the limiting stops 40 and 42 engage the followers 30 and 29, respectively. In other words, the draft movement is limited by the castings which move in unison with the draw bar. Upon inward or 10 buffering movement of the draw bar, it is apparent that the followers 28 and 31 will remain stationary since they are held by the block 25 and webs 32, respectively. The remaining followers 30 and 29 will be forced inwardly by means of the castings 35 and such inward movement will continue until 15 the rear face 45 of the draw bar butt engages the front face 46 of the block 26 and the limiting stops 41 and 43 engage the followers 28 and 31, respectively. From the foregoing, it will be seen that the castings 20 25 also limit the inward movement of the draw bar and the compression of the springs.

The parts are shown assembled in the drawing. To remove the same, it is apparent that the keys 12, 21 and 22 are first taken out whereupon the castings 35, springs and followers and the blocks 25 and 26 can be removed forwardly as a unit. The parts are assembled in the reverse manner as will 30 be obvious. It is apparent that the followers and springs are supported and guided by the lower bar or casting 16.

Although I have herein shown and described what I now consider the preferred 40 embodiment of the invention, the same is merely illustrative and I contemplate all changes and modifications that come within the scope of the claims appended hereto.

I claim:

45 1. In a draft rigging, the combination with a draw bar, and cushioning mechanism including followers, of means connected with the draw bar for actuating said followers, said means having a series of shoulders thereon and limiting stops.

50 2. In a draft rigging, the combination with a draw bar, and a series of centrally located fixed abutments, of cushioning means including followers, interposed between and normally engaging said fixed abutments, and castings co-operating with said followers at their ends, the castings having a plurality of stop shoulders and being slidably mounted and adapted to be actuated by the draw 55 bar.

60 3. In a draft rigging, the combination with a draw bar, fixed abutments and followers engaging said abutments, of movable plates for actuating the followers, said plates

having main and limiting stop shoulders for 65 co-operation with said followers.

4. In a draft rigging, the combination with a draw bar, three centrally located fixed abutments providing a pair of pockets therebetween, tandem arranged springs and followers within said pockets, of slidably mounted side members co-operating with said followers, said side members being movable in unison with the draw bar and having means thereon for limiting the compression 75 of the springs.

5. In a railway draft rigging, the combination with spaced parallel draft sills, of a plurality of longitudinally spaced, fixed abutments disposed between said sills and spaced therefrom, of cushioning means including followers interposed between and normally engaging said fixed abutments, and a pair of castings mounted between the sills, each of said castings being adapted to slide 85 on the inner face of a sill and interposed between the latter and adjacent ends of the followers, each of said castings having vertically extending shoulders engaging the followers for actuating the same, a draw 90 bar, and means for operatively connecting said draw bar and castings.

6. In a draft rigging, the combination with tandem arranged springs and followers, and fixed abutments co-operating with 95 said followers, of castings having tandem arranged stop shoulders thereon co-operable with said followers, said castings being longitudinally slidably, said stop castings being provided with limiting stops to thereby limit 100 the compression of the springs.

7. In a draft rigging, the combination with sills, a draw bar, cushioning means, and castings connected to and movable in unison with the draw bar, of fixed abutments co-operable with the cushioning mechanism, the castings and cushioning mechanism being insertible longitudinally as a 105 unit between the sills.

8. In a draft rigging, the combination 110 with upper and lower, longitudinally extending fixed bars, of three sets of fixed abutments extending vertically between said bars, two of said abutments being removable, tandem arranged cushioning mechanism interposed between the three abutments, and a draw bar for actuating the tandem arranged cushioning mechanism.

9. In a railway draft rigging, the combination with spaced parallel draft sills, of a plurality of longitudinally spaced fixed abutments disposed between said sills, of cushioning means including followers interposed between and normally engaging said fixed abutments, and a pair of castings 115 mounted between the sills, each of said castings being adapted to slide on the inner face of a sill and interposed between the latter 120 and the followers.

and adjacent ends of the followers, each of said castings having vertically extending main stop shoulders normally engaging the followers and vertically extending limiting 5 stop shoulders adapted to engage the followers to limit the compression of the cushioning means.

In witness that I claim the foregoing I have hereunto subscribed my name this 18th day of Sept., 1916.

JOHN F. O'CONNOR.
